(57) **CLAIM**

The ornamental design for a telescopic glasses shield, as shown and described.

DESCRIPTION

FIG. 1 is a front and top perspective view of a telescopic glasses shield, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an exploded view thereof, showing arms of the telescopic glasses shield in a folded position; and,

FIG. 9 is a perspective view thereof, showing the arms of the telescopic glasses shield in a retracted position.

The dashed broken lines in the figures illustrate portions of the telescopic glasses shield that form no part of the claimed design.
